(57) **CLAIM**

The ornamental design for a mounting block, as shown and described.

DESCRIPTION

FIG. 1 is a perspective view of a mounting block in accordance with our invention;

FIG. 2 is a side view thereof, an opposing side view being a mirror image thereof;

FIG. 3 is a front view thereof, an opposing rear view being a mirror image thereof;

FIG. 4 is a top view thereof; and,

FIG. 5 is a bottom view thereof.

Shading used in the drawings illustrates surface contours, and does not form a part of the claimed design. The dashed lines in the drawings show environmental structure and form no part of the claimed design.
